UNITED STATES PATENT OFFICE.

HERMANN PERLICH, OF BALTIMORE, MARYLAND.

FUMIGATOR.

SPECIFICATION forming part of Letters Patent No. 315,330, dated April 7, 1885.

Application filed August 23, 1884. (No model.)

To all whom it may concern:

Be it known that I, HERMANN PERLICH, a citizen of the United States, residing at Baltimore, in the State of Maryland, have invented 5 certain new and useful Improvements in Fumigators, of which the following is a specification.

My invention relates to certain improvements in fumigators of that class shown in 10 Letters granted me February 27, 1883, and December 4, 1883, numbered, respectively, 273,144 and 289,553.

The object of this invention is to provide 15 a detachable smoke-dome to surmount the top of fumigators, and a receptacle in which to burn sulphur when said receptacle is inclosed within the fire-pot of the fumigator.

In the accompanying drawings, Figure 1 is 20 a side view of the fumigator, showing the smoke-dome in position. Fig. 2 is a view, separately, of the smoke-dome. Fig. 3 is a top view of the sulphur-burning receptacle. Fig. 4 is a vertical section of the receptacle and base or ash-pan. Fig. 5 shows the detachable bail of the fumigator employed to lift 25 the sulphur-receptacle.

The letter A designates the base or ash-pan, to which the fire-pot B is connected by 30 the hooks c on the base engaging with the knobs d on the fire-pot. The top plate, e, of the fire-pot is perforated with numerous small holes to afford escape for the fumes. The small holes e' are shown in Fig. 1, where 35 a portion of the wall is broken away, and said top is rigidly fixed to its position, and is not intended to be removed. The bail I is made of wire or other suitable material, and each end terminates in an open hook, k, in order that it may be readily detached from 40 the ears L, which are secured to the sides of the fire-pot. The smoke-dome F has a crown, g, perforated with numerous small holes, and side walls, h, with air-inlets i. It is provided with one, two, or more spring-clamps, j, which 45 are adapted to press against the rim of the top plate, e, of the fire-pot. Thus constructed, the smoke-dome may be attached to or removed at pleasure from the fumigator. When in position, this dome serves to cool the hot fumes issuing from the fire-pot and to mingle air with 50

said fumes. The cool air enters the inlets i, and within the dome mixes with the fumes which then issue from the perforated crown g.

The sulphur-burning receptacle N is a shallow-pan vessel with tight or imperforate walls and bottom, and having an outward horizontal top flange, p, with draft-perforations q all around it. It is also provided with bail-ears r. This receptacle is to occupy the base or ash-pan A, the outward top flange, p, fitting 55 snugly within the wall of the said ash-pan. An annular space, s, is thereby formed between the receptacle and said pan-wall. By this construction the receptacle is prevented from moving in the pan, and air to maintain 60 the draft has free passage through the holes in the pan-wall and thence up through the perforations q in the top flange. The bail I may be detached from the fire-pot and hooked to the ears r of the sulphur-receptacle, and thereby the latter, while hot, may be lifted 65 from the ash-pan and emptied or submerged in water to extinguish the burning sulphur. By this arrangement one bail serves for the 70 two purposes, and the removable receptacle 75 for burning sulphur alone adapts the fumigator to a wider range of uses—namely, for fumigating hospitals, sick-rooms, or ships, and as an aid in the extermination of certain 80 dangerous diseases.

For the ordinary fumigation of hot-houses and like places where plants are kept, thoroughly-soaked tobacco-stems may be employed, in which case a removable grate or bottom, as shown in my patent of December 85 4, 1883, should be employed. For hospitals, ships, and such places, sulphur alone should be used. The sulphur-burning receptacle N may be used when a grate or bottom is in the lower end of the fire-pot B; or it may be used 90 without such grate. For certain purposes—such as for rose-houses, where there is mildew on the plants—powdered sulphur may be intermingled and packed with the tobacco-stems.

Having described my invention, I claim and desire to secure by Letters Patent of the United States—

1. A fumigator having a fire-pot, B, provided with a perforated top plate, e, and sur- 95

mounted by a smoke-dome, F, having a perforated crown, and side walls with air-inlets, as set forth.

2. A smoke-dome for fumigators having a 5 perforated crown, g, and side walls with air-inlets i, and provided with spring-clamps j for its attachment to the top of the fumigator, as set forth.

3. In a fumigator, the combination of a fire-pot, B, provided with a top plate having perforations, a smoke-dome, F, having perforations in its crown and air-inlets in its wall, an

ash-pan having holes in its side wall, and an imperforate receptacle, N, having an outward top flange, P, provided with draft-perforations, said receptacle occupying the ash-pan, as set forth. 15

In testimony whereof I affix my signature in presence of two witnesses.

HERMANN PERLICH.
